UNITED STATES PATENT OFFICE.

CHARLES C. FIELD, OF NEW YORK, N. Y.

DESIGN FOR A WAGON-HUB BAND.

SPECIFICATION forming part of Design No. 22,469, dated May 23, 1893

Application filed April 1, 1893. Serial No. 468,708. Term of patent 14 years.

To all whom it may concern:

Be it known that I, CHARLES C. FIELD, of the city, county, and State of New York, have invented a new and original Design for a 5 Wagon-Hub Band, of which the following is a full, clear, and exact description.

Reference is to be had to the accompanying drawings, forming a part of this specification, in which similar letters of reference indicate 10 corresponding parts in both the figures.

Figure 1 is a perspective view of a wagon hub band embodying my design; and Fig. 2 is a sectional side elevation of the same as arranged on the hub.

The leading feature of my design consists 15 of the annular internal bead or flange A on the inside of the band B at the front edge thereof; the said internal bead or flange being approximately half round in cross section.

I claim—

20 The design for a wagon hub band as herein shown and described.

CHARLES C. FIELD.
